UNITED STATES PATENT OFFICE.

LEAH G. MILKES, OF MINNEAPOLIS, MINNESOTA.

COMBINATION SLEEPING-ROBE AND PINNING-BLANKET.

1,236,586.

Specification of Letters Patent. Patented Aug. 14, 1917.

Application filed November 4, 1913. Serial No. 799,072.

To all whom it may concern:

Be it known that I, LEAH G. MILKES, a citizen of the United States, residing at Minneapolis, in the county of Hennepin and State of Minnesota, have invented certain new and useful Improvements in Combination Sleeping-Robes and Pinning-Blankets; and I do hereby declare the following to be a full, clear, and exact description of the invention, such as will enable others skilled in the art to which it appertains to make and use the same.

My invention has for its object to provide an improved garment for infants in the nature of a combination sleeping robe and pinning blanket, and to such ends, generally stated, the invention consists of the novel devices and combinations of devices herein-after described and defined in the claim.

The invention is illustrated in the accompanying drawings wherein like characters indicate like parts throughout the several views. Referring to the drawings:

Figures 1, 2 and 3 are perspective views showing the garment applied in several different ways;

Fig. 4 is a plan view showing the waist section of the garment;

Fig. 5 is a plan view showing the blanket section of the garment spread out flat; and

Fig. 6 is an enlarged detail in section on the line $x^6 x^6$ on Fig. 5.

The waist section of the garment is indicated as an entirety by the numeral 1 and the blanket section thereof, is indicated by the numeral 2. This blanket 2 is preferably in the form of a sort of a truncated diamond, the truncated, or cut off upper portion thereof, being parallel to an imaginary line drawn through the transversely opposite corners of the blanket. The whole blanket is preferably provided with a hem 2^a and the horizontal upper edge thereof is formed with button holes 3 and 4. The button holes 3 are in an alined row and they are adapted to be attached to buttons 5 on the lower edge of the waist 1.

The numeral 6 indicates a pad preferably made up of a layer of absorbent material

and a layer of rubber sheeting. This pad 50 is provided at its upper edge with short straps 7, provided with buttons 8 adapted to be buttoned into the holes 4 of the blanket 2. The pad is, therefore, made detachable, so that the blanket and the pad may be independently laundried and at the same time, when the pad is attached to the blanket, it is held in proper position.

Also, as is evident, the waist 1, being detachable from the blanket, may be independently laundried, but this is even more important for other reasons presently to be noted.

The garment may be used in a great many different ways, for instance, for using on a small infant at night, or for sleeping purposes, the blanket is attached to the waist and is folded, as shown, in Fig. 1, and its corners are attached to its body portion, preferably by safety pins indicated at 9. 65 When used on a small infant in the day time, the blanket would preferably be applied as already noted in the description of Fig. 1, but with the waist removed, as shown in Fig. 2. The said waist would be removed 70 because in the day time a dress or other garment would be usually placed on the infant.

The garment is also well adapted to be worn by a child beginning, or who is learning to walk (see Fig. 3) and when thus worn, the blanket 2 may be used as a diaper. In all of the instances above noted, the pad 1 may be used or not, as desired, but it would preferably be employed in all instances, and 80 when employed, is, as already noted, held in proper position in respect to the blanket.

What I claim is:

An infant's sleeping blanket comprising a waist portion and a leg portion detachably 90 connected thereto, the latter being in the form of a truncated diamond having unbroken edges, the truncated portion corresponding to the waist line of said waist portion and the two transverse points of the 95 diamond adapted to lap one over the other, the overlapping point being secured to the underlying portion at the opposite side edge

of the blanket and in the front thereof, and the central or depending point of the diamond adapted to be upwardly folded and overlie both of the overlapping side portions, and a relatively small water-proof pad detachably secured to the upper central portion of said blanket, and terminating so short of the lower end that the latter

may be drawn between the legs of the wearer without drawing the pad with it.

10

In testimony whereof I affix my signature in presence of two witnesses.

LEAH G. MILKES.
